DESIGN FOR A POWDER AND PERFUME CONTAINER

Robert Baxter, New York, N. Y., assignor to Prince Matchabelli Perfumery, Inc., New York,
N. Y., a corporation of New York

Application May 18, 1936, Serial No. 62,695

Term of patent 7 years

To all whom it may concern:

Be it known that I, Robert Baxter, a citizen of the United States, residing at New York, county of New York, and State of New York, have invented a new, original, and ornamental Design for a Powder and Perfume Container, of which the following is a specification, reference being had to the accompanying drawing, forming a part thereof.

Figure 1 is a top plan view of a powder and perfume container, showing my new design; and Figure 2 is a side elevational view thereof.

I claim:

The ornamental design for a powder and perfume container substantially as shown.

ROBERT BAXTER.
